UNITED STATES PATENT OFFICE.

GEORGE W. FARRIER, OF MILWAUKEE, WISCONSIN.

DESIGN FOR A KNEE MEMBER FOR ARTIFICIAL LEGS.

SPECIFICATION forming part of Design No. 34,275, dated March 26, 1901.

Application filed February 1, 1901. Serial No. 45,660. Term of patent 14 years.

To all whom it may concern:

Be it known that I, GEORGE W. FARRIER, a citizen of the United States of America, residing at Milwaukee, in the county of Milwaukee and State of Wisconsin, have invented and produced a certain new, useful, and original Design for an Article of Manufacture—to wit, a Knee Member for Artificial Legs—of which the following is a specification, reference being had to the accompanying drawings, forming a part thereof.

In said drawings, Figure 1 is a side view in elevation of a knee member for artificial legs embodying my design. Fig. 2 is a side view, in cross-section, of the same. Fig. 3 is a back view in elevation of the same. Fig. 4 is a top view of the same, these four views being deemed necessary for full illustration.

The design resembles a shell-like sleeve from the top to an offset portion and has its front substantially straight, while its sides converge slightly toward said offset portion.

From the lower edge of the offset portion in front my design proceeds down and around on an irregular curve to a point 2 in the rear.

The rear or back of my design from a point

3 to the offset portion proceeds on a straight line, and from the lower edge of said offset portion to the point 2 it proceeds on a straight line.

The whole takes the form on its surface like unto the form of the portion of the human leg from a short distance above the knee to the under side of the knee-cap when the leg is wholly bent. The rear of the shell is provided with an elongated opening from the point 3 to a point 4 in its bottom. In each side of the shell is a rectangular opening 5, surrounded by a flange 6 on the inside of the shell. The outer surface of the shell at the back between points 2 and 3 is flattened, as shown in Fig. 3.

Having thus described my design, what I claim is—

The design for a knee member for artificial legs, substantially as shown and described.

Signed by me at Philadelphia, Pennsylvania, this 22d day of January, A. D. 1901.

GEORGE W. FARRIER.
